(57) **CLAIM**

The ornamental design for a battery charger for earphones, as shown and described.

DESCRIPTION

FIG. 1 is a top, front and left side perspective view of a battery charger for earphones;

FIG. 2 is a front elevation view thereof;

FIG. 3 is a rear elevation view thereof;

FIG. 4 is a top plan view thereof;

FIG. 5 is a bottom plan view thereof;

FIG. 6 is a left side elevation view thereof;

FIG. 7 is a right side elevation view thereof;

FIG. 8 is a front, top and left side perspective view thereof, showing the battery charger for earphones with the lid opened;

FIG. 9 is a front elevation view thereof, showing the battery charger for earphones with the lid opened;

FIG. 10 is a rear elevation view thereof, showing the battery charger for earphones with the lid opened;

FIG. 11 is a top plan view thereof, showing the battery charger for earphones with the lid opened;

FIG. 12 is a bottom plan view thereof, showing the battery charger for earphones with the lid opened;

FIG. 13 is a left side elevation view thereof, showing the battery charger for earphones with the lid opened;

FIG. 14 is a right side elevation view thereof, showing the battery charger for earphones with the lid opened;

FIG. 15 is an end-elevational view taken along the 15-15 line of FIG. 2;

FIG. 16 is an end-elevational view taken along the 16-16 line of FIG. 2; and,

FIG. 17 is an end-elevational view taken along the 17-17 line of FIG. 4.

(Continued)

The broken lines shown in the drawings illustrate portions of the battery charger for earphones that form no part of the claimed design.
